UNITED STATES PATENT OFFICE

MAURICE JOSEPH CHARLES MARIE THOMAS, OF TROBERTVILLE, FRANCE

ROTATABLE FLUID CURRENT MACHINE

Application filed January 25, 1929, Serial No. 334,985, and in Belgium February 9, 1928.

The present invention relates to rotatable fluid current machines and, more especially, to those adapted to be driven by a liquid.

One of the objects of the invention is to render the operation of machines of the above type more sure and regular irrespective of the direction and the velocity of the current by which they are driven.

Other objects will appear in the course of the detailed description now to be given with reference to the accompanying drawings, in which:—

Fig. 1 is a perspective of one illustrative embodiment of the invention;

15 Figs. 2 to 5 are diagrams showing the relative positions of the various elements at different phases of the machine's operation.

Referring to the various figures of the drawings, there is shown an assembly consisting of a vertical rotatable shaft *a* supported at both ends in appropriate bearings,—a rectangular frame *b* supported by collars *c*¹, *c*², and including a pair of rotatable side members *b*¹ and *b*²,—a pair of vanes *d*¹ and *d*² adapted to rotate with *b*¹ and *b*² respectively,—pairs of transverse rods *e*¹, *e*² and *e*³, *e*⁴ traversing elements *b*¹ and *b*² respectively,—flexible cables *f*¹, *f*² and *f*³, *f*⁴ passing over pulleys supported on collar *c*¹, and terminating in springs *h*¹, *h*², *h*³, *h*⁴ connected to a collar *i* attached to shaft *a*,—and a speed regulating device to be described further on.

The above assembly placed in a horizontal current of liquid flowing in any given direction operates substantially as follows:—

When vane *d*¹ is in the position shown in Figs. 1 and 2 relatively to current *x*, it moves so that the impulse received from said current is at a maximum i. e. so that spring *h*¹ is completely distended, while spring *h*² is completely slack. In this position, which corresponds to one of the extreme positions of the vane, the plane of the latter takes a position on the current side of shaft *a*, this position being determined by the maximum tension of spring *h*¹ and the length of cable *e*¹ (angle *y*). Vane *d*², at the same time assumes the position shown in Figs. 1 and 2 i. e. substantially in line with the current and

so that spring *h*⁴ is slightly stretched while *h*³ is slightly slack, whereby favoring the rotation of shaft *a*. The current, continuing to act on vane *d*¹, repels it towards the position shown in dotted lines in Fig. 3, when it ceases to be further impelled by the current. The tension of spring *h*¹ then acts to rotate vane *d*¹ so that it presents its opposite face to the current and moves into the full line position represented in Fig. 3, spring *h*¹ becoming 60 completely relaxed, while spring *h*² is stretched to a maximum and limits the extreme position of the vane. The current acting on panel *d*¹ continues to rotate shaft *a* in the same direction until the former approaches the position corresponding to that of vane *d*² in Figs. 1 and 2. As the vane approaches the position shown in Fig. 5—passing through the position corresponding to that of vane *d*² in Fig. 3—spring *h*² relaxes 70 until *h*¹ and *h*² are equally stretched, then spring *h*¹ stretches to a maximum bringing vane *d*¹ into driving position (Fig. 5).

Shaft *a* is, therefor, driven by vane *d*¹ while frame *b* is displaced from the position shown 75 in Fig. 5 to that in which the plane of the frame is substantially perpendicular to direction *x* i. e. through 270°. Vane *d*¹ is inactive, therefor, only for 360°—270°=90°.

Since two vanes *d*¹ and *d*² are employed, 80 angularly displaced by 180° from one another, a continuous drive of shaft *a* is obtained, irrespective of the direction of current *x*.

If desired, a series of frames may be positioned along shaft *a* with their planes displaced by an appropriate angle, i. e. 90° for two frames, 60° for three frames etc. so as to increase the force and uniformity of the rotative couple. 85

The hereinabove described assembly may, if desired, be fitted with a speed regulating device comprising weights *j*, *j*, mounted on arms *j*¹, *j*² which articulate with a fixed collar *k* driven by shaft *a*, and controlling arms *f*² supporting collar *i*. When shaft *a* turns at too high a speed, masses *j*, *j* are thrown outwardly and move collar *i* upward so as to slacken all of the springs *h*. Frame *b* will, therefore, have to describe a greater angle 95 100

than that for which vane d^1 moves into driving position (Fig 5) before the reaction of the current can be transmitted to shaft a . If the speed diminishes, springs h are brought under tension and increases the driving period.

What I claim is:—

In combination, a rotatable shaft, a frame mounted on said shaft, a plurality of vanes pivotally mounted in said frame, a collar 10 slidable on said shaft, a control rod associated with each of said vanes and extending on opposite sides thereof, flexible cables connected to said control rods on either side of each 15 of said vanes, springs connected to said cables and to said collar, and means controlled by the speed of rotation of said shaft to move said collar along the shaft to vary the tension of said springs.

20 In testimony whereof I have signed this specification.

MAURICE JOSEPH CHARLES MARIE THOMAS.
